TIE PLATE ARRANGEMENT FOR RAILROADS

Original Filed Aug. 18, 1934

UNITED STATES PATENT OFFICE

2,110,894

TIE PLATE ARRANGEMENT FOR RAILROADS

Theodore W. Stedman, New York, N. Y., assignor, by direct and mesne assignments, to Resilient Products Corporation, New York, N. Y., a corporation of New York

Application August 18, 1934, Serial No. 740,371
Renewed June 10, 1937

6 Claims. (Cl. 238—302)

My invention relates to tie plate arrangements adapted for railroad use.

My invention has particular reference to a tie plate formed from resilient and metallic members associated in face-to-face relation and disposed between the railroad rail and its supporting cross tie.

Various other objects, advantages and features of my invention will become apparent from the following detailed description.

My invention resides in the tie plate arrangements, features and improvements of the character hereinafter described and claimed.

In some respects, the tie plate arrangements of this application are an improvement on the invention disclosed in my pending application Serial Number 690,084, filed September 19, 1933.

For an understanding of my invention and for an illustration of some of the forms thereof, reference is to be had to the accompanying drawing, in which:

Figure 1 is a perspective view of a tie plate arrangement as constructed in accordance with my invention;

Fig. 2 is a plan view of a section of a railroad track;

Fig. 3 is a transverse, vertical sectional view showing my novel tie plate associated with a railroad rail and its supporting cross tie;

Fig. 4 is a view taken longitudinally of the railroad rail and showing my novel tie plate in vertical section.

Fig. 5 is a fragmentary, vertical sectional view showing a part of my novel tie plate arrangement; and

Fig. 6 is a perspective view of a tie plate arrangement of a modified form.

Referring particularly to Fig. 2, T represents the wooden cross ties and R the parallel steel rails of a railroad track. The rails R do not contact directly with the ties T since, in accordance with my invention, tie plates P of novel construction are disposed between the base of each rail R and the upper surfaces of the respective ties T.

As indicated on the drawing, the tie plate P of one form of my invention is formed from a harness jacket or metallic member a and a resilient member or shoe b associated together in face-to-face relation and disposed in operative position with the resilient member b resting upon the cross tie T and serving as a support for the metallic member a and the rail R.

As illustrated, the metallic member or harness jacket a is of generally rectangular plate-like configuration. It is provided with spaced up-

standing flanges or shoulders a1 disposed in parallel relation and having a width between their inner surfaces slightly greater than the width of the base of the rail R. Extending downwardly through these flanges a1 are the vertical passages a2 through which are adapted to extend the respective fastening members or track spikes S having heads which overlie the base of the rail at its upper surface. Outwardly of each of the flanges a1, the metallic member a may be formed with the vertical passages a3 through which are adapted to extend the respective fastening members or screw spikes S1 which extend downwardly into the cross tie.

As illustrated on the drawing, the aforesaid metallic member a, between the flanges a1, is provided with an opening or passage a4 of square, rectangular or other suitable configuration. This opening a4 should be of substantial area and, as shown, it is desirable for the dimension thereof laterally of the railroad track to correspond approximately with the distance between the inner surfaces of the flanges a1. Preferably, the dimension of said opening a4 longitudinally of the railroad track should correspond substantially with the aforesaid lateral dimension and, under such conditions, the metallic member a, between the flanges a1, comprises only the ribs or webs a5 which extend transversely with respect to the railroad track.

The aforesaid resilient member or shoe b comprises a sole plate or base section b1 having a lower flat surface adapted to rest upon the upper flat surface of its supporting cross tie T. Said resilient member b further comprises an upstanding, centrally disposed cushion section b4 having an upper flat surface, slightly canted if desired, upon which rests the lower flat surface of the rail R. As illustrated, this upstanding resilient section b4 extends upwardly into the aforesaid opening a4 of the metallic member a and, as clearly shown on the drawing, the upper surface of said resilient section b4 is disposed a substantial distance above the upper surfaces of the ribs a5 of the metallic member a.

Preferably, in accordance with the invention, the upstanding section b4 of the resilient member b corresponds in configuration with that of the opening a4 of the metallic member a in the sense that the dimensions of said upstanding section b4 should be at least slightly less than those of said opening a4 so as to facilitate assembly of the parts.

As the parts are positioned in Fig. 3, it clearly appears that the base section b1 of the resilient

member *b* is provided with inner vertical passages *b*2 alined respectively, with the aforesaid passage *a*2 of the member *a*. Further, said base section *b*1 is provided with the outer vertical passages *b*3 which are in alinement with the respective passages *a*3 of the member *a*.

In accordance with the disclosure of my aforesaid pending application, it is desirable that the lateral dimensions of the passages *b*2 and *b*3 be smaller than the lateral sectional area of the spikes *S* and *S*1 which extend therethrough, respectively.

Further, in accordance with the general disclosure of my aforesaid pending application, it is desirable that sheet-like reinforcing means *c* be disposed in the base section *b*1 of the resilient member *b*, Fig. 5. Such reinforcing means *c* may be of any suitable character consonant with operating requirements. At present, however, said reinforcing means *c*, preferably, is of fabric or cord material which is suitably embedded in the base section *b* of said member *b*.

Preferably in accordance with the invention, the aforesaid metallic member *a* is formed from a rolled section of steel while the resilient member *b* is formed from suitable resilient material, such as natural rubber, synthetic rubber, or its equivalent, a pad of substantially non-absorbent fibrous or fabric material enveloped by some agent such as rubber, latex or the like, etc. Accordingly, as the parts are shown on the drawing, it clearly appears that the tie plate arrangement of my invention presents rubber or rubber-like surfaces which contact with the cross tie and rail, respectively. At the same time, said tie plate arrangement of my invention, because comprising the metallic member *a*, embodies the advantageous features existing with respect to the metallic tie plates of the prior art.

It clearly appears, therefore, that, with the tie plate arrangement of my invention as hereinbefore described, rubber surfaces or equivalent are presented at all points between the traffic load and the cross ties which ultimately support such load. In a sense, the rubber material may be said to be largely massed directly beneath the rail, this being desirable because the downward pressure of the traffic load is concentrated in this area. At the same time, there is the desirable distribution of a thinner layer of rubber beneath the outer surfaces of the metallic member *a* to thereby prevent direct contact of the metallic member *a* with the cross tie, with the attendant advantages, and to cushion the impact effect transmitted to this area.

The tie plate arrangement of my invention presents the highly desirable characteristic of providing reinforcing means which, as regards the rubber material, substantially increases the compressional resistance and the tensile strength resistant to spreading when subjected to the weight of traffic. To this end, the upstanding section *b*4 of the resilient member *b* is rather closely confined by the surfaces of the metallic member *a* defining the opening *a*4. Further, the use of the reinforcing means *c* is highly advantageous as regards the characteristic noted above.

As stated above, it is desirable that the passages *b*2 and *b*3 of the resilient member *b* be smaller in a lateral sense than the transverse dimensions of the respective spikes *S* and *S*1. This is advantageous, particularly, in connection with wooden cross ties *T* because of largely sealing the spike holes and preventing the entrance of moisture thereto. Because of so doing, decay

is retarded to thereby lengthen the life of the cross ties. It shall be understood, however, that my invention is not to be limited in the respects last noted nor is the invention to be limited to the use of wooden cross ties. This is necessarily true inasmuch as a resilient tie plate arrangement of the character described herein is particularly advantageous in connection with railway installations involving the use of concrete or steel cross ties because of introducing an element of resiliency which is otherwise lacking therein.

In Fig. 6, I have illustrated a modified form of the invention. As shown, there is provided a metallic member *a*10 which is of the same general character as the above described metallic member *a* with the exception that the opening or passage *a*4 is omitted. In lieu thereof, the metallic member *a*10, during the rolling operation, is provided with a depression *a*11 which may be bounded by the flanges *a*1 and by the upper surfaces of the ribs or webs *a*5. In accordance with the invention, this depression *a*11 more or less snugly receives a pad *b*11 of suitable flexible material which may be of the character hereinbefore described, the upper surface of said pad terminating a suitable distance above the upper surfaces of the ribs *a*5.

As will readily be understood, the base of the rail is adapted to rest upon the upper surface of the aforesaid pad *b*11 to thereby cushion the shock of traffic. The metallic member *a*10 may rest directly upon the cross tie or, between said metallic member and cross tie, there may be interposed a pad corresponding with the resilient member *b* but with the section *b*4 omitted.

In view of all the foregoing, it becomes obvious that my novel tie plate arrangements are particularly advantageous from a practical viewpoint. In a very important sense, the tie plates of my invention cushion the shock of traffic. They thereby serve to lengthen the life of the roadbed and the rolling stock. The expense item for repairs is decreased. Noise and the unpleasant effects thereof incident to traffic operation is largely decreased. These and many other advantages are characteristic of my invention.

If desired, the lower surface of the resilient member *b* may have a layer of closely woven, single or multi-ply, rubberized fabric vulcanized or otherwise suitably secured thereto. This fabric, then, contacts with the cross tie and protects the rubber material from the effects of creosote or the like.

In the appended claims, the references to "cross ties" shall be understood as generically describing and including any wooden, metal, concrete or other supporting structure for the railroad rails.

While my invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In a tie plate arrangement, a shoe of rubber-like material, said shoe comprising a sole plate adapted to be supported on the cross tie of a railroad track, and a cushion section of rubber-like material formed integrally with said sole plate and extending upwardly therefrom, said cushion

- section being smaller in horizontal cross section than said sole plate and being adapted to support a railroad rail, said sole plate comprising a section extending outwardly beyond each vertical surface of said cushion section whereby the latter is disposed entirely within the border of said sole plate, said outwardly extending sections being adapted to cooperate with a harness jacket for supporting the latter on the cross tie.
5. In a tie plate arrangement, a shoe of rubber-like material, said shoe comprising a sole plate adapted to be supported on a cross tie of a railroad track, a cushion section of rubber-like material formed integrally with said sole plate and extending upwardly therefrom, said cushion section being smaller in horizontal cross section than said sole plate and being adapted to support a railroad rail, and sheet-like reinforcing means disposed in the plane of said shoe, said sole plate comprising a section extending outwardly beyond each vertical surface of said cushion section whereby the latter is disposed entirely within the border of said sole plate, said outwardly extending sections being adapted to cooperate with a harness jacket for supporting the latter on the cross tie, the respective sections of said sole plate beyond opposite vertical surfaces of said cushion section being provided with passages adapted to receive fastening means.
10. In a tie plate arrangement, a shoe comprising a sole plate adapted to be supported by the cross tie of a railroad track, a harness jacket supported by said sole plate, said harness jacket comprising spaced sections adapted for attachment to said cross tie, said spaced harness jacket sections being connected together by spaced ribs disposed in substantially parallel relation, said spaced harness jacket sections and said ribs defining a passage extending vertically through said harness jacket, and a cushion section extending from said sole plate upwardly through the passage of said harness jacket and terminating above the upper surfaces of said ribs, the railroad rail being adapted to be supported by the upper surface of said cushion section, said sole plate protecting the cross tie against abrasion throughout the area thereof which is in engagement with said cross tie.
15. In a tie plate arrangement, a shoe of rubber-like material, said shoe comprising a sole plate adapted to be supported on a cross tie of a railroad track, a harness jacket resting on said sole plate and supported thereby free from contact with said cross tie, said harness jacket having a passage extending vertically therethrough, and a cushion section of rubber-like material formed integrally with said sole plate and extending therefrom upwardly through said passage, said cushion section being adapted to support a railroad rail and being higher than those surfaces of the harness jacket directly beneath said rail, said sole plate and harness jacket being provided with aligned openings through which are adapted to extend the respective fastening members which secure the tie plate arrangement to the cross tie, said fastening members causing the sole plate and the harness jacket to remain in fixed position with respect to each other whereby said cushion section is properly positioned within the passage of said harness jacket.
20. In a tie plate arrangement, a shoe of rubber-like material, said shoe comprising a sole plate adapted to be supported on the cross tie of a railroad track, a harness jacket resting on said sole plate and supported thereby free from contact with said cross tie, said harness jacket having a passage extending vertically therethrough, and a cushion section of rubber-like material formed integrally with said sole plate and extending therefrom upwardly through said passage, said cushion section being adapted to support a railroad rail and being higher than those surfaces of the harness jacket directly beneath said rail, the horizontal area of said cushion section, when free from the weight of traffic, being less than the horizontal area of said passage.
25. In a tie plate arrangement, a shoe of rubber-like material, said shoe comprising a sole plate adapted to be supported on the cross tie of a railroad track, and a cushion section of rubber-like material formed integrally with said sole plate and extending upwardly therefrom, said cushion section being smaller in horizontal cross section than said sole plate and being adapted to support a railroad rail, said sole plate comprising sections extending outwardly beyond opposite vertical surfaces, respectively, of said cushion section, said outwardly extending sections being adapted to cooperate with a harness jacket for supporting the latter on the cross tie.
30. In a tie plate arrangement, a shoe comprising a sole plate adapted to be supported by the cross tie of a railroad track, a harness jacket supported by said sole plate, said harness jacket comprising spaced sections adapted for attachment to said cross tie, said spaced harness jacket sections being connected together by spaced ribs disposed in substantially parallel relation, said spaced harness jacket sections and said ribs defining a passage extending vertically through said harness jacket, and a cushion section extending from said sole plate upwardly through the passage of said harness jacket and terminating above the upper surfaces of said ribs, the railroad rail being adapted to be supported by the upper surface of said cushion section, said sole plate protecting the cross tie against abrasion throughout the area thereof which is in engagement with said cross tie.
35. In a tie plate arrangement, a shoe of rubber-like material, said shoe comprising a sole plate adapted to be supported on the cross tie of a railroad track, a harness jacket resting on said sole plate and supported thereby free from contact with said cross tie, said harness jacket having a passage extending vertically therethrough, and a cushion section of rubber-like material formed integrally with said sole plate and extending upwardly therefrom, said cushion section being smaller in horizontal cross section than said sole plate and being adapted to support a railroad rail, said sole plate comprising sections extending outwardly beyond opposite vertical surfaces, respectively, of said cushion section, said outwardly extending sections being adapted to cooperate with a harness jacket for supporting the latter on the cross tie.
40. In a tie plate arrangement, a shoe of rubber-like material, said shoe comprising a sole plate adapted to be supported on the cross tie of a railroad track, a harness jacket resting on said sole plate and supported thereby free from contact with said cross tie, said harness jacket having a passage extending vertically therethrough, and a cushion section of rubber-like material formed integrally with said sole plate and extending upwardly therefrom, said cushion section being smaller in horizontal cross section than said sole plate and being adapted to support a railroad rail, said sole plate comprising sections extending outwardly beyond opposite vertical surfaces, respectively, of said cushion section, said outwardly extending sections being adapted to cooperate with a harness jacket for supporting the latter on the cross tie.
45. In a tie plate arrangement, a shoe of rubber-like material, said shoe comprising a sole plate adapted to be supported on the cross tie of a railroad track, a harness jacket resting on said sole plate and supported thereby free from contact with said cross tie, said harness jacket having a passage extending vertically therethrough, and a cushion section of rubber-like material formed integrally with said sole plate and extending upwardly therefrom, said cushion section being smaller in horizontal cross section than said sole plate and being adapted to support a railroad rail, said sole plate comprising sections extending outwardly beyond opposite vertical surfaces, respectively, of said cushion section, said outwardly extending sections being adapted to cooperate with a harness jacket for supporting the latter on the cross tie.
50. THEODORE W. STEDMAN.
